A. H. EKMAN & P. J. GALLAGHER.
DISINFECTANT CONTAINER.
APPLICATION FILED DEC. 8, 1914.

1,155,343.

Patented Oct. 5, 1915.

UNITED STATES PATENT OFFICE.

ALBERT H. EKMAN AND PATRICK J. GALLAGHER, OF SPOKANE, WASHINGTON.

DISINFECTANT-CONTAINER.

1,155,343.

Specification of Letters Patent.

Patented Oct. 5, 1915.

Application filed December 8, 1914. Serial No. 876,036.

To all whom it may concern:

Be it known that we, ALBERT H. EKMAN and PATRICK J. GALLAGHER, citizens of the United States, residing at Spokane, in the 5 county of Spokane and State of Washington, have invented certain new and useful Improvements in Disinfectant-Containers, of which the following is a specification.

The object of this invention is to provide 10 an improved form of disinfecting container for retention and purification of articles which are used upon various parts of the person, such articles as tooth brushes and the like.

15 It is well known that matter which settles upon the teeth and which is removed by a tooth brush, contains a great deal of bacteria which if allowed to propagate would render a tooth brush extremely unhygienic and 20 totally unfit for use after a short period of time. If on the contrary, the tooth brush is thoroughly disinfected after each application of use, the brush may be properly employed throughout the life of the bristles 25 thereof.

Now it is one of the features of this invention to provide a container having an open portion, which, is preferably in the form of an open bottom, and which is maintained closed by a novel form of closure structure.

In the most improved embodiment of the 35 invention, the closure structure includes a container for the disinfectant, which may be in the form of a capsule and which is held by the closure structure in an interior position with respect to the container.

Other features and objects of the invention will be more fully described in connection 40 with the accompanying drawing, and will be more particularly pointed out in and by the appended claims.

In the drawing:—Figure 1 is a view in side elevation illustrating one form of the 45 invention. Fig. 2 is a sectional view on line 2—2 of Fig. 1. Fig. 3 is a plan view of the device shown in Fig. 1. Fig. 4 is a sectional view on the line 4—4 of Fig. 2 with the parts on an enlarged scale. Fig. 5 is a detail perspective view of the capsule or disinfectant container.

Like characters of reference designate similar parts throughout the different figures of the drawing.

55 As illustrated, the improved container is embodied in a tube of transparent material,

such as glass, as indicated at 1, the upper end 2 being closed and the lower end 3 being open. In the form shown it is intended to support the container in an inverted position and the same is provided with a bead 4 somewhat nearer the closed than the open end. A support 5 is provided which may be in the form of a clip, having embracing 60 spring terminals 6 between which the container 1 may be inserted so as to support the latter not only by frictional engagement with the clip terminals but also by engagement therewith of the bead 4. The support 5 may be secured to a wall or the like in any 65 desirable manner, as indicated at 7.

The improved closure structure includes an open ended ferrule 8 which is shown interiorly threaded for threaded engagement with exterior threads on the open portion or lower end 3, of the container 1. The ferrule 8 is provided with an inturned gasket or packing flange 9, whereby a ring packing or gasket 10 may be interposed between the flange 9 and the lower margin of the open 75 end 3. One portion of the flange 9, as indicated at 11, is extended radially inwardly to form a support for a disinfectant holder 12, illustrated as being formed integral with flange 9. The holder 12 is perforated, as indicated at 13, and a cap 14 provides for 80 efficiency of tar extraction.

In order to close the lower end of the container 1, a closure 15 is provided which is shown hinged, as at 16, to the ferrule 8. A 90 suitable spring fastener 17, mounted on the closure 15, engages ferrule 8 above a bead 18 thereon in such a manner as to retain the closure 15 in the closing position shown in full lines in Fig. 4. Tight closure may be effected by seating a disk gasket or packing 19 in the bottom of closure 15 so that when the latter is moved into a closing position, the gasket 19 will be tightly impinged between the packing flange 9 and the closure 15.

The container 1 is preferably formed of a transparent material, such as glass, and the closure 15 not only functions to close the container 1, but also to form a support for holding an article in the container, such article being illustrated as a tooth brush 20 which is supported by closure 15, and which is automatically released from the container 1 when the closure 15 is opened.

We preferably use a disinfectant which 110 generates a gas when the air in the container 1 is moistened by the moisture of the

bristles of the tooth brush so that the gas will thoroughly permeate the bristles and destroy the germs. When the moisture in the air has been taken up by generation of the disinfecting gas, the disinfectant material will then no longer be drawn upon and therefore a single capsule or charge of such material will last for a considerable length of time.

10 It will be readily seen that when the container is to be cleaned, the ferrule 8 may be turned off from the threaded end of the container 1 leaving the latter entirely accessible for the insertion therein of a suitable cleansing instrument. Furthermore, the container may be readily detached from its support so as to be immersed in a boiling fluid.

15 It is believed that the advantages and 20 utility of this invention will be fully understood from the foregoing description, and while only one specific form thereof has been shown, it will be understood that the invention is not to be limited to such specific 25 showing except for such limitations as the claims may import.

We claim:—

1. In a disinfecting device, a container 30 having a threaded open portion, a closure device for said open portion comprising an open ended threaded ferrule adapted to be turned onto said portion and having a gasket engaging flange, a ring gasket interposed between said flange and said portion, a disinfectant holder carried by said ferrule and disposed interiorly of said container, a closure hinged to said ferrule for closing the open end of said container, and a disk gasket interposed between said closure and the 40 flange of said ferrule, substantially as described.

2. In a disinfecting device, a container having a threaded open portion, a support 45 for said container disposing the same with its open portion downwardly, a closure device for said open portion comprising an open ended threaded ferrule adapted to be turned onto said portion and having a gasket engaging flange, a ring gasket interposed between said flange and said portion, a disinfectant holder carried by said ferrule and disposed interiorly of said container, a closure hinged to said ferrule for closing the 50 open end of said container, and a disk gasket interposed between said closure and the flange of said ferrule, substantially as described.

3. In a disinfecting device, a tubular container having a closed and an open end, a support for holding said container in an inverted position with its open end downwardly, a ferrule secured to the open end of

said container and provided with a disinfectant holder disposed interiorly of said container, and a closure hinged to said ferrule for closing the container and supporting the article to be disinfected therein, substantially as described.

4. In a disinfecting device, a tubular container having a closed and an open end, a support for holding said container in an inverted position with its open end downwardly, a ferrule secured to the open end of said container and provided with a disinfectant holder disposed interiorly of said container, and a closure for attachment to said ferrule for closing the open end of said container and supporting the article to be disinfected therein, substantially as described.

5. In a disinfecting device, a tubular container having a closed and an open end, a ferrule secured to the open end of said container and provided with a disinfectant holder disposed interiorly of said container, and a closure for attachment to said ferrule to close the open end of said container for direct engagement with the article to be disinfected to prevent discharge of the article from said container, substantially as described.

6. In a disinfecting device, a tubular container having a closed and an open end, a ferrule secured exteriorly about the open end of said container and having a disinfectant holder disposed interiorly of the container and nearer one portion of the wall thereof than another to permit free passage of the article to be disinfected into and out of said container laterally of said holder, and means attachable to the ferrule for closing the open end of the container, substantially as described.

7. In a disinfectant device, a container having an open portion, an open ended ferrule having one end secured to the open portion of said container and having a disinfectant holder rigidly secured thereto and disposed interiorly of the container when said ferrule is attached to the latter, and a closure hinged to said ferrule for closing the remaining end of the latter and the open portion of said container and forming an abutment for direct engagement by the article in said container to prevent discharge of the article from the latter, substantially as described.

In testimony whereof we affix our signatures in presence of two witnesses.

ALBERT H. EKMAN.

PATRICK J. GALLAGHER.
